UNITED STATES PATENT OFFICE.

STEPHEN O. HEINDL, OF CHICAGO, ILLINOIS, ASSIGNOR OF ONE-HALF TO ERNEST ZEITZ, OF CHICAGO, ILLINOIS.

RAZOR-GRINDER.

1,393,283.

Specification of Letters Patent. Patented Oct. 11, 1921.

Application filed August 21, 1920. Serial No. 405,050.

To all whom it may concern:

Be it known that I, STEPHEN O. HEINDL, a former subject of the Emperor of Austria, (who has declared his intention of becoming an American citizen,) residing at Chicago, in the county of Cook and State of Illinois, have invented certain new and useful Improvements in Razor-Grinders, of which the following is a specification.

10 My invention relates to grinding machines and more specifically to an improved machine for grinding razor blades.

15 The primary object of the invention is to provide an efficient machine for grinding the concave sides of razor blades or any similarly shaped tools.

Another object is to provide a work holding means permitting of continued and speedy operation of the device.

20 A further object is to embody such a machine in a relatively compact and simple structure, easy to manufacture and durable in service.

25 Further objects and advantages of my invention will become apparent as the description proceeds.

In the accompanying drawings, Figure 1 is a side view of an illustrative embodiment of my invention, certain parts being broken away. Fig. 2 is an end view of the grinding wheel supporting and driving means. Fig. 3 is a section through the work holder slides showing the work holder in end elevation. Fig. 4 is a plan view of the main 30 frame member of the detachable work rest, and Fig. 5 is a side view of the work rest partly in section. Fig. 6 is a section through the work holding clamp. Fig. 7 is an end view and Fig. 8 a longitudinal section of the mounting at the front end of the work carriage slides. Fig. 9 is a section showing the mounting of the grinding shaft brackets of the feed shaft. Fig. 10 is a section on line 10—10 of Fig. 9, and Fig. 11 is a central longitudinal section through one of the grinding shaft brackets.

In the embodiment of my invention selected for illustration, four legs 10 support a frame 12 at its corners and are preferably 50 braced by cross pieces 14 to form a rigid structure. T-shaped standards 16 mounted opposite each other on the sides of the frame 12 support three transverse shafts comprising two guide shafts 18 and a feed shaft 20. 55 A pair of brackets 22 are slidably supported

on the guide shafts 18 and may be fed toward and away from the center of the machine simultaneously by means best illustrated in Fig. 9 comprising right and left hand screw threads on the feed shaft 20 engaging nuts 24 seated in counterbores in the bracket casting and prevented from rotation by suitable pins 26 entering circular apertures defined by semi-circular notches in the nuts 24 and brackets 22. Each bracket carries a shaft extending longitudinally of the machine and journaled in suitable bearings 28 carried by the bracket. One of the shafts 30 carries a drive pulley 32 near the front end of its bracket and the other shaft 34 carries a similar drive pulley 36 near the rear end of its bracket. The brackets 22 are pressed against the nuts 24 by suitable compression springs 38 encircling the feed shaft 20 which feed shaft may be rotated by a handle 40 to move the grinding wheels toward and away from the work.

I have provided suitable means for delivering power to the shafts 30 and 34 to drive the grinding wheels carried thereby in the 80 directions indicated by the arrows in Fig. 3. Referring to Figs. 1 and 2, a drive shaft 42 carries a tight pulley 44 and a loose pulley 46 to which power may be delivered by a belt from any suitable source. Brackets 48 clamped on the legs 10 slidably support the longitudinally extending rod 50 carrying belt shifting fingers 52 and a suitable handle 54 preferably at the front end of the machine. The shaft 42 also carries a pulley 56 connected by belt 58 to the pulley 32 on the shaft 30. The drive shaft 42 and a similar shaft 60 are journaled in suitable bearings in brackets 62 and 64 depending from the frame 12, and project at the rear end of 95 the machine to carry gears 66 for connecting the shafts to drive them in opposite directions at equal speeds. A suitable gear cover 68 may be employed to protect the gears. Shaft 34 is driven from a pulley 70 on shaft 60 by a suitable belt 72. It will be seen that the pulleys 44 and 46 are so arranged that the belt may extend therefrom laterally past the transmission to shafts 30 and 34 at any convenient angle in either direction.

For supporting the work in proper vertical adjustment with respect to the grinding wheels and moving it into engagement therewith, I provide a longitudinally reciprocating frame or carriage carrying a detachable 100

work holder. Referring to Figs. 1 and 3, a vertical frame member or carriage 74 is enlarged to form journals 76 for slidably supporting the same on guide rods 78 and 5 has a central enlargement 80 in which the plunger 82 is fastened. A plate 84 overlies the upper cross piece 90 of the carriage 74 and is slidably supported for vertical adjustment by means of stud bolts 88 threaded 10 into the same and extending downwardly in suitable sliding engagement with the ends of the cross pieces 90 and 92 at the upper and lower ends of the carriage. A yoke 94 is fastened on the ends of bolts 88 and has threaded engagement with a vertical adjusting screw 96 rotatably but non-slidably mounted in the cross piece 92 and carrying a knurled hand wheel 98 or other suitable means for rotating it to adjust the height of 15 the plate 84.

A guide 100 is carried by the plate 84 on which the detachable work carrier is supported. This work carrier comprises a main work supporting element illustrated in Fig. 25. 4 comprising a front portion 102 having the irregular cross section illustrated in Fig. 3, a central portion 104 having slots 106 cut in its opposite sides, and a cylindrical stem 108. Suitable clamping members 110 rest 30 in the slots 106 and may be drawn toward each other by means of a wing nut 112 and bolt 114 to securely clamp the handle 116 of a razor or other similar tool, the blade of which rests on the narrow upper edge of 35 the front portion 102.

For detachably mounting the work carrier I provide a guideway in the portion 102 engaging the guide carried by the plate 84 and quick detachable stop means for holding 40 the work holder against longitudinal displacement on the guide. The means illustrated for this purpose comprises a rotatable sleeve 118 on the stem 108 carrying a radially projecting pin 120 and resiliently urged 45 in a certain direction by a coiled spring 122 preferably housed within the sleeve. The rotation of the sleeve may be limited to approximately 90 degrees by engagement of projecting lug 124 on the stationary cap 128 50 with the ends of the cutaway portion 126 in the sleeve. As the holder slides into place, the pin 120 encounters the beveled end 130 of plate 84 and is deflected thereby, passing down the side of the plate and snapping 55 into a slot 132 to hold the parts securely in position.

The means I have provided for reciprocating the carriage 74 on the guides 78 comprises the large gear wheel 134 journaled on 60 a shaft 137 supported at its rear end by the bracket 62 and at its front end by a supporting strip 136 which strip also supports the rear ends of the guide rods 78 and is braced at its ends by rods 138 extending forwardly

from the bracket 62. This gear is driven 65 from the pinion 140 mounted on the shaft 42 and carries a cam 142 adapted to engage the roller 144 carried by the end of the plunger 82 to reciprocate the same axially against the force of a compression spring 147. The 70 plunger extends slidably but non-rotatably through a face plate 148 (see Fig. 8) mounted in the end of a tube 150 supported on the frame 12, which tube also functions to support the front ends of the guide rods 78 by 75 means of ears 151 receiving said guide rods. An enlarged head 152 at the front end of the plunger normally reciprocates, as shown in Fig. 8, from the position shown in the drawings to a position at the rear end of the 80 cavity 154 defined by a sleeve 156 rotatably supported inside the tube 150 but prevented from axial movement by a suitable pin 158 entering an annular groove 160. The head 162 on the sleeve 156 may be rotated by a 85 suitable handle 164 to draw a nut 166 splined on the plunger 82 toward the right and limit the movement of the plunger to any desired extent. This adjustment may be used to determine the length of stroke used. The nut 90 may also be moved to the right until the plunger is clamped in stationary position with the spring 147 compressed and the roller 144 held out of contact with the cam 142.

Water or other suitable coolant may be delivered to the grinding wheels 168 as by means of a nozzle 170 and will be received in a tank 172 located beneath the grinding wheels. This tank preferably includes lateral portions extending as indicated in dotted lines at 174, past the cam 142 and gear 134, and the walls may be cut away to allow for the guide rods 78 and plunger 82.

In operating my device, when it is first 105 adjusted for use, a razor will be clamped in position on the detachable work holder and the work holder slid along guideways 102 until the radial pin 120 snaps into the slot 132. The grinding wheels 168 are withdrawn from contact with the work and the work advanced to position between them, in which position the vertical height of plate 84 may be adjusted to properly position the work between the wheels. The machine is 110 then started and the operator advances the grinding wheels by turning the crank 40 until the razor is properly ground. To insert a new piece of work, the operator may rotate the sleeve 118 without stopping the machine 115 and withdraw the work holder from its guides, the ends of which are slightly tapered for a short distance to facilitate removal and replacement of the work holder. A new piece of work may then be substituted 120 for the finished piece or a different holder with the new work already clamped in place 125 may be substituted for the one removed, and

the work holder slid back on the guideways and pushed forward until the pin 120 engages slot 132 without stopping the machine.

It will be obvious that if desired, however, 5 the machine may be readily stopped as an entirety by means of handle 54, or the carriage 74 may be drawn back by a few turns of the sleeve 156 to hold it stationary in its forwardmost position clear of the grinding 10 wheels.

While I have illustrated and described in detail the preferred embodiment of my invention, it should be clearly understood that the disclosure is merely for purposes of illustration and that many modifications and 15 variations will naturally occur to those skilled in the art. I aim in the subjoined claims to cover all such legitimate variations and modifications.

20 I claim as my invention:

1. In a device of the class described, a pair of grinding wheels, a reciprocatory carriage adapted to carry a piece of work to and fro between said wheels, and manually 25 adjustable means for limiting the longitudinal displacement of said carriage in its reciprocatory movement between said wheels simultaneously with the continuation of said movement.

30 2. In a device of the class described, a pair of grinding wheels, a carriage adapted to carry a piece of work to and fro between said wheels, automatic cam means for reciprocating said carriage, and manual 35 means for limiting the reciprocatory displacement of said carriage simultaneously with its operation.

3. In a device of the class described, a pair of grinding wheels, a reciprocatory carriage having a tapered end and a lateral slot, a tool holder having longitudinal slideable attachment to said carriage for supporting a tool in position to be moved between said grinding wheels by the movement 45 of said carriage, a cylindrical stem fixed to the holder, a sleeve manually rotatable on said stem between certain stopped positions, a radial pin fixed in said sleeve adapted to slidably engage the tapered end 50 of said carriage and normally rest in said slot to secure said tool holder against longitudinal displacement on said carriage, and resilient means tending to hold said pin in engagement with said slot.

55 4. In a device of the class described, a pair of grinding wheels, a reciprocatory carriage having a tapered end and a lateral slot, a tool holder having longitudinal slideable attachment to said carriage for supporting a tool in position to be moved between 60 said grinding wheels by the move-

ment of said carriage, a cylindrical stem fixed to the holder, a sleeve manually rotatable on said stem between certain stopped positions, a radial pin fixed in said sleeve 65 adapted to slidably engage the tapered end of said carriage and normally rest in said slot to secure said tool holder against displacement, and spring means coacting with said stem and said sleeve tending to rotate 70 the latter in position to cause engagement of said pin with said slot.

5. In a device of the class described, a pair of grinding wheels, a reciprocatory carriage having a slideway, a tool holder 75 mounted on said slideway for supporting a tool in position to be moved between said grinding wheels by the movement of the carriage, and manual means for removing the holder from and replacing it on said 80 carriage without interrupting the reciprocatory movement thereof, said means comprising a manually movable handle mounted on said tool holder, a member fixed on said handle and adapted to engage said carriage 85 in one position of the handle to prevent relative movement of said tool holder and said carriage, and resilient means tending to hold said member in such engagement with said carriage.

6. In a device of the class described, a pair of grinding wheels, a carriage adapted to carry a piece of work to and fro between said wheels, automatic cam means for reciprocating said carriage in one direction, 95 resilient means for moving said carriage in the other direction, and manually controlled means for limiting the extent of movement of the carriage caused by said resilient means.

100 7. In a device of the class described, a pair of grinding wheels, a reciprocatory carriage adapted to carry work between said wheels, automatic cam means for moving said carriage in one direction, resilient means for moving said carriage in the other direction, a plunger movable with said carriage, a flanged head on the end of said plunger, a fixed tube, an internally screw-threaded sleeve rotatable within said tube and 105 adapted to receive said head, an externally screw-threaded bushing slidably but non-rotatably mounted on said plunger and adapted to engage said sleeve internally and form an abutment for said head, and means 110 for rotating the sleeve to variously position said bushing therein and limit the movement of said plunger.

In testimony whereof, I have hereunto set my hand.

STEPHEN O. HEINDL.
